UNITED STATES PATENT OFFICE.

KATHARINE PYLE, OF WILMINGTON, DELAWARE, ASSIGNOR TO M. H. BIRGE & SONS, OF BUFFALO, NEW YORK.

DESIGN FOR WALL-PAPER.

SPECIFICATION forming part of Design No. 23,815, dated November 20, 1894.

Application filed September 25, 1894. Serial No. 524,112. Term of patent 3½ years.

To all whom it may concern:

Be it known that I, KATHARINE PYLE, a citizen of the United States, residing at Wilmington, in the county of New Castle and State of Delaware, have invented and produced a certain new and original Design for Wall Paper, of which the following is a specification.

The leading features of the design consist of the representation of Red Riding Hood, the wolf and the grandmother as represented in the accompanying drawing, in which the figure of a girl carrying a basket is arranged in the center. The figure of a wolf clothed in garments with a hat in its front paw is arranged on one side and the figure of the grandmother on the opposite side of the center figure. The top of the border is formed of a narrow band

containing daisies connected by ribbons and the bottom of the border is formed by a wider band containing daisies and small ornaments as shown. The above border is accompanied with a wall paper containing groups of daisies tied by flowing ribbons and arranged irregularly over the paper as shown in the drawing.

What I claim is—

The design for wall paper herein shown and described.

Witness my hand this 21st day of September, 1894.

KATHARINE PYLE.
